PATTERN HAVING INTEGRAL VENT-FORMING MEMBERS

Raymond J. Miller, Detroit, Mich.

Application January 18, 1943, Serial No. 472,719

16 Claims. (Cl. 22—113)

This invention relates to the art of casting, and more particularly to the production of molds formed of plastic or granular substances such as plaster having venting runners or openings formed therein in an improved manner to permit the ready escape of entrained air or gases created during the casting operation.

Fine grained substances such as plaster of Paris or gypsum for use as mold-forming substances have been considered for a long time. Difficulties have been experienced in venting molds formed of such fine grained substances because of the virtual impossibility of forming venting runners or openings to permit the ready escape of entrained air and gases formed when molten alloy or metal is introduced into the casting cavity.

In the Capaco process of plaster molding as described in Patent No. 2,210,037, issued May 14, 1940, relatively porous molds are formed to permit the dissipation of entrained air and gases through the walls of the mold-forming substance. No venting passages are employed in such molds, and the only communication between the casting cavity and the atmosphere other than through the walls of the mold-forming substance is through the gate and sprue provided to admit molten alloy to the casting cavity.

In the Capaco process porosity of the mold-forming substance is achieved by adding excess water to gypsum powder reinforced by asbestos fibre. The excess water is dispelled by a drying or curing operation to leave voids or open spaces in the portions of the mold formerly occupied by the water. If too large a quantity of water is employed, the mold will be too weak to withstand the pouring stresses to which it is subjected when molten alloy is introduced into its cavity to form a casting. If too small a quantity of water is employed, the resulting mold does not possess sufficient porosity to enable the entrained air and gases to escape with a sufficient degree of rapidity. In molds having the highest possible permeability consistent with providing the necessary strength to withstand the pouring stresses, the molten alloy must be introduced quite slowly to enable the entrained air and gases to diffuse through the walls of the mold. The molten alloy frequently chills and solidifies before the casting cavities are completely filled, whereupon inferior castings result.

Difficult problems are also encountered in maintaining the gypsum powder suspended in the liquid until the mold has attained a predetermined set to provide a homogeneous mold. Elaborate

shaking or agitating means have been required to keep the powder in motion until the necessary predetermined mold set has been attained.

My invention overcomes these difficulties and provides a stronger and more homogeneous mold by providing novel and improved venting passages in the cope section of the mold whereby entrained air and gases formed during the casting operation may be readily dispelled from the casting cavity.

5 An object of this invention resides in the formation of cooperating patterns having a parting extended to the top of the pattern to provide a venting passage in the cope section of molds formed from the patterns.

10 Another object is to provide an improved method of forming molds having integrally-formed venting passages.

15 A further object of the invention is to provide molds having venting passages leading from portions of the casting cavities positioned so that they would become isolated as molten alloy or metal is poured into a mold to form a casting.

20 An additional object resides in the formation of a novel and improved method of venting molds whereby the isolation of casting cavity sections during the pouring of the mold is prevented.

25 Another object is to provide improved venting means for a mold formed from a plurality of die patterns positioned in a flask wherein vent passage-forming bars carried by each die pattern communicate with a venting outlet associated with the flask.

30 Yet a further object of the invention is to provide an improved method of venting die pattern-formed molds of gypsum material whereby more durable molds having greater density capable of producing castings having smoother surface texture may be formed.

35 Still another object resides in the formation of 40 cooperating cope and drag molds having improved venting means formed by extending the parting line to a point adjacent the upper extremity of the casting cavity in the cope mold.

45 An additional object of this invention is to provide production pattern equipment formed by a reproductive process and having vent passage-forming members carried thereby.

50 A further object resides in the formation of gypsum molds having feeding passages communicating with the lowermost portions of the casting cavities to minimize turbulence resulting from the introduction of molten alloy or metal to form castings.

55 Yet another object of the invention resides in the formation of pattern-carrying blocks having

impression-forming runner members to permit feeding of molten alloy or metal adjacent the bottom of a casting cavity and to permit the escape of entrained air and gases from the top of the casting cavity.

Another object is to provide an improved method of venting casting cavities by means of venting passages extending through various sections of the mold and capable of being successively isolated as molten alloy or metal reaches them without interrupting the venting action of other portions of the venting system.

Other objects and advantages of this invention will be apparent from the following detailed description considered in connection with the accompanying drawings, submitted for purposes of illustration only and not intended to define the scope of the invention, reference being had for that purpose to the subjoined claims.

In the drawings wherein similar reference characters refer to similar parts throughout the several views:

Fig. 24 is a fragmentary sectional view taken substantially on the section line 24—24 of Fig. 25 of the assembled cope and drag molds formed from pattern equipment of the type illustrated in Fig. 1 wherein the cope casting cavity is formed from the pattern impression 36 of Fig. 1 and illustrating the venting of portions of the casting cavity projecting to different vertical heights above the parting line between the cope and drag molds.

Fig. 25 is a fragmentary plan view of the casting cavity of the cope mold, taken substantially on the line 25—25 of Fig. 24 looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

While this invention is applicable to all types of pattern equipment and the molds formed therefrom, it is illustrated herein as applied to molds and patterns of the so-called die pattern type wherein a plurality of pattern-carrying blocks 10, 12, 14, etc., are removably mounted in a flask 16. The pattern-carrying blocks 10, 12, 14, etc., are carried by frames 18, 20, 22, etc., detachably connected to the bottom plate 24 of the flask 16 by means of screws 26. A separator member 28 preferably extending transversely of the flask 16 may be provided to divide the space within the flask into two separated pattern-receiving compartments.

A feeder-forming runner 30 may be positioned on the separator member 28 to form a feeder impression 31 in the cope mold 33 to conduct molten alloy or metal from the space formed in the mold by a feeder-forming member 32 to the casting cavities 35 formed in the mold investment by the pattern impressions 34, 36, etc., carried by the blocks 10, 12, etc., respectively.

The feeder-forming runner 30 connects with riser-forming members associated with each of the patterns carried by each pattern block 10, 12, 14, etc. For example, riser-forming members 38 and 40 on the pattern blocks 10 and 12 provide chambers to receive a supply of shrinkage compensating molten alloy or metal, connected with the feeder-forming runner 30 by controlled feeder-forming impressions 42 and 44. Surge pool formers 46 and 48 respectively are positioned adjacent the riser-forming members 38 and 40 to reduce turbulence of the molten alloy or metal introduced into the casting cavities. The riser-forming members connect with the pattern impressions by way of controlled feeder-forming members such as the impressions 50 and 52 carried by the pattern blocks 10 and 12 respectively.

The frames 18, 20, 22, etc., are formed to accurate external dimensions in three planes and

are of graduated sizes so that a pattern-carrying frame of proper size may be selected to accommodate a particular pattern. The space within the flask 16 may thus be efficiently used, since a plurality of patterns of the same or different sizes may be used simultaneously to form cope or drag molds having casting cavities conforming to the contours of the various patterns employed.

Die patterns are of the so-called separated pattern-plate type and are used in pairs in the formation of cope and drag molds cooperating to provide the desired casting cavities. The cope and drag pattern members of each pair of co-operating pattern blocks are accurately positioned with reference to the edges of their associated pattern-carrying frames, and since the frames are accurately positioned in the flask 16, assurance is had that the pattern impressions in the cope and drag molds will accurately align to form the desired casting cavity.

The production pattern equipment on the pattern-carrying blocks 10, 12, 14, et cetera, may be formed by the reproductive method as disclosed in my copending applications Serial No. 421,115, filed December 1, 1941 (M-17), and Serial No. 454,831, filed August 14, 1942 (M-23). This production pattern equipment may be formed from separated complementary master pattern members or from a unitary master pattern formed of wood or of any other suitable material.

Where a unitary master pattern is employed, it may be embedded in any suitable parting material, such for example as molding clay, wax, plaster of Paris, paraffin, etc., up to its normal parting plane to divide the pattern into vertically-spaced sections having no back draft. The parting material may be contoured adjacent the edge of the pattern to extend the parting to the top of the cope pattern to accommodate the venting runners employed to permit the escape of entrained air and gases from the casting cavity. The parting material may also be contoured to drop the parting down to the bottom of the casting cavity to permit the feeding of alloy or metal at the bottom of the casting cavity to prevent turbulence in the flow of the metal when pouring the mold. The parting line need not be straight, but must be continuous around the periphery of the model.

A female impression of the exposed portion of the pattern and the surface of the parting material may be formed in a frame in any suitable moldable substance, such for example as alloys of the bismuth antimony base including cerro-base possessing the characteristic of flowing and solidifying with negligible change of volume. The assembly may then be inverted, the parting material removed, and another female impression formed in the same type of material of the then exposed portion of the pattern and the exposed surface of the female impression formerly made. These complementary female impressions may be separated, the pattern removed, and the female impressions used in the formation of production patterns.

Where the pattern equipment is being reproduced from separated pattern segments, female impressions of each segment may be formed in suitable frames, and the production pattern equipment formed from these female impressions.

Where so-called match-plate patterns are desired, the female impressions of vertically-spaced portions of the desired pattern may be positioned on opposite sides of a pattern-carrying frame and

suitable moldable substance introduced into the space within the frame and the female impressions to form a matched-plate pattern having the desired complementary pattern impressions on opposite sides of a single plate as more clearly illustrated in my copending application Serial No. 465,234, filed November 11, 1942 (M-33).

Where separated patterns of the die pattern type are to be formed, the pattern-carrying frames 18, 20, 22, etc., may be superimposed on and aligned with frames of the same dimensions having the female impressions of the desired pattern. The production patterns may then be formed by introducing into the space within the frames a moldable substance capable of filling the female impression and the space within the pattern-carrying frames 18, 20, 22, etc. Many types of substances are suitable for forming the production pattern equipment, such for example as white metal, alloys of aluminum, the bismuth antimony base alloys such for example as cerro-base, cerrobend, and cerromatrix, etc. If the substance of which the female impressions and the production patterns are formed do not possess the characteristic of substantially constant volume upon solidification, suitable allowance should be made to compensate for the variation.

Great flexibility and accuracy are involved in the formation of pattern equipment by the reproductive process, and in view of the facility with which the parting may be extended vertically, it is possible to achieve results not heretofore practical.

Referring now to Figures 1 to 4, the pattern 36 on the pattern-carrying block 10 is a cope pattern of a connecting rod having a central body portion 34 having spaced rigidifying webs 56 and 58 and large and small end connections 60 and 62.

In the formation of the pattern 36 the master model corresponding with the contour of the pattern 36 is embedded in the parting material, and the parting material is applied to the edges of the model to provide tapered or angularly-disposed sections 64 and 66 adjacent the large and small ends 60 and 62 respectively. Venting strips 68 and 70 are formed on the tapered sections 64 and 66 respectively and preferably extend to the end of the block 10 remote from the feeder.

The venting strips 68 and 70 may be reproduced from any convenient, preferably pliable substance applied directly to the parting material before the female impression is formed. The tapered sections 64 and 66 extend the parting to the top of the high sections of the pattern and are tapered angularly as illustrated to facilitate separation of the pattern from the female impression during the formation of the pattern equipment, and the separation of the mold from the pattern when molds are formed.

The venting strips 68 and 70 communicate preferably at the end of pattern-carrying block 10 with a venting strip 72 extending transversely across the end of the block 10 and communicating with a vent riser 74 carried by the flask 16 by means of a venting strip 76 positioned on the flask.

As illustrated on an enlarged scale in Figure 2, the parting of molds formed from the patterns is extended down adjacent the feeder runner 30 to permit feeding molten alloy or metal adjacent the bottom of the casting cavity of the molds formed from the pattern equipment. The feeder-forming member 42 communicating with the feeder runner 30 is disposed angularly to lead the molten substance down through the surge pool-

forming member 46 into the riser-forming member 38 communicating with the casting cavity through the controlled feeder-forming member 50. As illustrated in Figs. 23 to 25 the vents 97, 99 and 101 being positioned adjacent the top of the high portions of the casting cavities of molds formed from the pattern remain open to permit the escape of air and gases until the casting cavity is completely filled, and the shrinkage compensating supply of molten alloy or metal in the riser chamber formed by the riser-forming member 38 maintains the casting cavity completely filled until solidification is complete.

The pattern 36 carried by the block 12 is illustrative of an irregularly shaped article having a plurality of portions 80, 82, 84 and 86 projecting above the surface of other portions of the pattern. These vertically extended portions of the pattern form impressions 81, 83, 85, etc., in the mold having no venting communication one with the other, or with the outside atmosphere during the pouring of molten alloy or metal into the mold when the alloy or metal rises above the surface of the mold cavity adjacent the vertically extended impressions 81, 83, 85, etc., of the portions 80, 82, 84 and 86 of the pattern. As illustrated, these high portions of the casting cavity of the mold formed from the pattern 36 may be readily vented by providing tapered sections 88, 90, 92 and 94 adjacent each of the vertically extended portions 80, 82, 84 and 86 respectively. The tapered sections 88, 90, 92, etc., form impressions 89, 91, 93, etc., in the cope mold 33 formed from the cope pattern 36 as illustrated in Fig. 25. Vent forming runner strips 96, 98 and 100 communicating with the topmost portions of the vertically extended portions 80, 82 and 84 of the pattern may communicate with a single vent forming runner strip 102 extending longitudinally of the pattern carrying block 12. The vent forming runner strips 96, 98 and 100 form vent runners 97, 99 and 101 extending along the tapered impressions 89, 91 and 93 respectively of the casting cavity of the cope mold 33, and these branch vent passages communicate with a single vent passage 103 communicating with a main vent passage 107 extending along the end of the mold as illustrated in Figs. 24 and 25. A vent forming runner 104 extends to the top of the tapered section 94 positioned adjacent the portion 86 of the pattern to form an impression of a vent runner in the mold to vent the portion of the mold formed therefrom. The longitudinally extended vent runners 102 and 104 communicate with a transversely extended vent runner 106 carried by the pattern block 12 and aligned with the transversely extended vent runner 72 carried by the pattern block 10 to form a main vent runner 107 in the mold to permit the escape of entrained air and gases through the venting opening formed by the vent riser 74.

It will be understood that the parting line 37 between the cope mold 33 and the drag mold 39 is contoured so that the drag mold 39 carries projections to close the tapered impressions 89, 91, 93, etc., and leave the vent passages 97, 99 and 101, etc., open to permit entrained air and gases to escape from the casting cavity when the mold is filled to form a casting.

Fig. 23 illustrates cope and drag molds 200 and 201 having a plurality of spaced casting cavities 202, 203 and 204 wherein the parting line 205 is contoured to extend to the top of the casting cavities 202, 203 and 204. Vent passages 206, 207 and 208 communicating with the top of the

casting cavities extend down the contoured parting to the normal parting line 205 between the cope and drag molds. All of the vent passages 206, 207 and 208 communicate with a single vent passage 209 extending along the parting line between the cope and drag sections of the mold to a main vent passage 210 extending across the end of the mold and communicating with atmosphere.

Figures 5 and 6 illustrate a somewhat modified form of the invention wherein a venting strip 110 is carried by the flask 16 along the marginal edges of the pattern block 10, 12, 14, etc. The longitudinally-extended venting strips 68 and 70 of the pattern block 10 and the longitudinally-extended strip 102 and 104 of the block 12 abut against the end of the transversely-extended strip 110 carried by the flask 16 to form the impressions of the vent system in the mold formed from the die patterns and flask. The vent riser-forming member 74 is preferably positioned at the opposite end of the flask 16 from the feeder-forming member 32.

After the pattern blocks have been formed in the manner indicated above and are assembled in the flask 16, the mold investment may be introduced into the flask to form the mold. Where plaster of Paris or gypsum is used as the mold investment, it is necessary only to add a sufficient quantity of liquid to chemically combine with the gypsum powder because the improved venting means permits the ready escape of entrained air and gases formed during the pouring operation.

The flask 16 is filled with the mold investment to a desired point above the highest portion of the pattern and riser members. After the mold has attained a predetermined set as by the use of a heating or curing operation, the pattern is extracted and the cope and drag molds are assembled for use in the formation of castings. The formation of the cope pattern only has been illustrated; however, it will be understood that the drag pattern will be complementary thereto to form cope and drag molds having the desired casting cavities corresponding with the contour of the pattern.

In the formation of the drag pattern equipment, the runner members applied to the parting material to form the vent passages are removed before the drag female impression is formed of the master model and parting material. The female impression from which the drag pattern equipment is formed thus embodies the contour of the parting material applied to extend the parting to the top of the cope pattern, but does not have the impressions of the venting runners. When molds are formed from the cope and drag pattern equipment, the impressions of the venting runners remain open to permit the ready escape of entrained air and gases formed during the pouring of the castings.

Figure 7 illustrates a fragmentary section of the cope mold 112 having an impression 114 of the vent riser 74. It will be noted that the mold closes over the top of the impression 114. The impression 114 is opened to atmosphere as illustrated in Figure 8 by projecting any suitable tool through the impression 114 to form the opening 116 to permit entrained air and gases to escape from the casting cavities through the venting network formed in the mold. It will be apparent that the vent-forming riser may extend through the top of the mold, if desired.

A vent riser may be positioned in the mold 112 to permit increasing the hydrostatic casting pres-

sure, if desired. Fig. 9 illustrates a vent riser 120 having a tapered lower edge 122 adapted to be introduced into the mold 112 above the impression 114 of the vent-forming member.

If desired, means may be provided to maintain each venting member open until its associated casting cavity is completely filled and prevent interruption of the main venting passages when a single vent positioned at a low level is closed.

As illustrated in Figures 10 to 12, a recess-forming member 126 may be positioned on the pattern-carrying block in alignment with the longitudinally-extending vent-forming member 70. When the mold investment is introduced into the flask to form the mold, it conforms to the shape of the recess-forming member 126 and embodies an enlarged recess in alignment with the venting passage 70.

A filter member, such for example as a synterized block 128 may be introduced into the recess 130 as illustrated in Figure 12. The block 128 is relatively porous and permits entrained air and gases to flow through it readily. When the casting cavity is completely filled, molten alloy or metal flows through the venting passage 132 formed in the mold 112. When the molten alloy or metal contacts the synterized block 128 it congeals because the porosity of the block is not sufficient to permit the alloy or metal to pass through. The individual venting passage is thus closed, and the main transversely-extending venting passage is not interrupted, but is maintained open to permit free venting of other portions of the casting cavity. It will be apparent that filter members or interrupting blocks can be positioned in branch-venting conduits, if desired, as between the longitudinally-extending venting conduits 102 and the branch conduits provided to vent the portions of the mold formed by the vertically-extended portions 80, 82, and 84 of the pattern 36.

The main vent riser preferably carried by the flask 16 may be closed after the casting cavity is completely filled to permit increasing the hydrostatic pressure without using a riser member as illustrated in Fig. 9. The vent riser 74 of Fig. 13 may be contoured, such for example as to provide a cylindrically-shaped portion 136 to form a seat for a filter member in the form of a synterized plug 138 as illustrated in Fig. 14. When the casting cavity has been completely filled and the need for venting eliminated, molten alloy or metal flowing down the main venting passage 130 formed by the vent-forming strip 76 contacts the synterized disc and congeals, whereupon the hydrostatic pressure may be increased, because the molten alloy or metal cannot escape through the venting riser.

The mold impressions formed from individual sections of the pattern may be conveniently vented by means of individual vents, if desired. As illustrated in Figure 15, a vent-forming member 142 may be positioned on any portion of the pattern to vent the casting cavity formed therefrom. The vent-forming member 142 is preferably provided with a contoured portion 144 to provide a seat for a filter member such as a synterized disc 146 in the mold 112 as illustrated in Figure 16. The disk 146 is preferably of a thickness equal to the depth of the cylindrical portion 144 to provide the mold 112 with a casting cavity with a smooth-textured surface accurately aligned with the remainder of the casting cavity.

When the mold has been formed with a vent

impression 148 conforming with the contour of the vent-forming member 142, the top of the mold may be broken out as indicated at 150 to permit the escape of entrained air and gases through the synterized disc. When the casting cavity is filled, the molten alloy or metal contacts the synterized disc 146 and stops. The synterized disc being fine-grained provides the vented portion of the casting with a smooth-textured surface.

The entire mold may be formed of synterized material, if desired, by introducing any suitable metal powder in the flask to conform to the shape of the pattern. The metal powder may then be synterized to bond it together to embody the contour of the pattern. Desirable substances for this purpose are synterized iron, brass, copper, bronze, etc. These synterized molds have a very high permeability and permit the ready escape of entrained air and gases without any venting means. Smooth-textured castings may be formed, because the synterized material has a fine-grained, smooth surface. It is possible to cast ferrous metals of virtually all types in synterized molds, because of the high melting point of the substances available for use in the formation of synterized molds. These molds are quite strong and do not distort after being synterized, and are fully capable of withstanding the stresses to which they are subjected.

Figures 17 to 21 illustrate a further modified form of the invention to prevent the venting system from becoming prematurely rendered inoperative where portions of the casting cavity to be vented are disposed at varying vertical heights.

The pattern 34 is provided with a vent-carrying member 152 adjacent each high portion of the pattern where venting of the casting cavity of the mold would be required. The vent-carrying member 152 communicates with the portion of the pattern where venting is required by means of a web or rib 154. A vent-forming strip 156 extends up the side of the vent-carrying member 152 across its top and down the opposite side to connect with a vent-forming strip 158 on the pattern-carrying block.

Where a pattern has a plurality of sections of varying vertical height used in the formation of molds having impressions extending above the adjacent surface of the mold and capable of becoming isolated as molten alloy or metal is introduced into the casting cavity, vent-carrying members 152 of a vertical height greater than the highest point of the pattern may be provided adjacent each portion of the pattern where venting is desired. The vent system is not interrupted when the lowest vented portion of the casting cavity is filled, because the remainder of the vent passages remain open until the entire casting cavity of the mold is filled. This result is accomplished because the vent-carrying members 152 are higher than any portion of the casting cavity.

It is of course only necessary to provide the venting system on the cope pattern. The web or rib 154 is slightly tapered as illustrated in Figure 18 to eliminate back draft. The vent-carrying member 152, web 154, and vent-forming strip 156 may be applied to the master model from which the pattern equipment is formed. The shape and contour of these venting members are reproduced in the female impression from which the production pattern equipment is formed by the reproductive method.

When the cope production pattern equipment

has been formed and positioned in the flask, mold-forming substance may be applied to form the cope portion of the mold. After the mold has been separated from the pattern, a plug 160 preferably formed of the same or similar material of which the mold is formed may be inserted into the hole formed by the vent-carrying member 152. The plug 160 fills the impression of the member 152, but leaves open the vent passage 162 formed in the mold by the vent-forming strip 156.

No provision need be made on the drag pattern for this venting system, because the plugs 160 inserted into the mold impressions of the vent-carrying members 152 confine the venting arrangement to the cope mold.

After the cope and drag molds 164 and 166 have been assembled as illustrated in Figure 21, molten alloy or metal may be introduced into the casting cavity 168 to form the desired casting. The casting 168 will have a rib or web 110 conforming to the shape of the web or rib 154 carried by the pattern. This rib 110 may be removed in any desired manner as by cutting or grinding, whereupon the casting will be ready for use.

As illustrated in Figure 20, the vent-forming strips 156 may be disposed at less than 180° relative to each other on the vent-carrying member 152, if necessary, because of space limitations.

Figure 22 illustrates an embodiment of the invention wherein a filtering plug 172 is inserted in a contoured aperture 174 in the mold body 112. The aperture may be formed by a suitable former similar to that illustrated in Figure 13. The filtering plug 172 may be used repeatedly, since it does not deteriorate with use. If the molten alloy or metal contacting the lower end of the plug shows a tendency to seal or close the pores of the synterized plug, the end of the plug may be sandblasted or machined slightly on a grinding wheel or any other suitable machine to recondition the plug for use. The plug may be used over and over again until it is worn down to substantially wafer thickness.

I claim:

1. A casting mold comprising cope and drag mold bodies cooperating to form a plurality of separate casting cavities having vertically extended portions having no venting communication one with the other when molten alloy or metal is introduced into the mold to form castings, a branch vent communicating with the top of each of said vertically extended portions and extending along the parting line between the cope and drag molds, a main vent interconnecting said branch vents with atmosphere, and means to interrupt the flow of molten alloy or metal through said branch vents to the main vent.

2. A mold having a casting cavity including a plurality of sections of different vertical height having no venting communication one with the other when molten alloy or metal is introduced into the casting cavity, vent passages communicating with the top of said sections of different vertical height, and a main vent passage interconnecting said vent passages with atmosphere, said vent passages being extended vertically to points adjacent the highest of said sections of different vertical height to prevent molten material from entering the main vent passage until the casting cavity is completely filled.

3. A mold comprising cope and drag members cooperating to form a casting cavity having a plurality of sections of different vertical height, 75

and vent passages communicating with the top of each of said sections of different vertical height and extending along the parting line between the cope and drag members of the mold.

5. A mold comprising cope and drag members cooperating to form a plurality of separate and independent casting cavities of different vertical height, and vent passages communicating with the top of each of said sections of different vertical height and extending along the parting line between the cope and drag members of the mold to vent each of the separate and independent casting cavities.

15. A mold comprising cope and drag members having a casting cavity including a plurality of sections of different vertical height having no venting communication one with another when molten alloy or metal is introduced into the casting cavity, branch vent passages communicating with the top of each of said sections of different vertical height and extending along the parting line between the cope and drag members of the mold, and a main vent passage extending along the parting line between the cope and drag members of the mold and connecting a plurality of the branch vent passages with atmosphere.

20. A mold comprising cope and drag sections having a casting cavity including a plurality of sections of different vertical height having no venting communication one with another when molten alloy or metal is introduced into the casting cavity, branch vent passages extending from the top of each of said sections of different vertical height interposed between the cope and drag sections of the mold, a main vent passage interconnecting a plurality of the branch vent passages, and check valve means between a plurality of the branch vent passages and the main vent passage to prevent molten alloy or metal from flowing into the main vent passage until the casting cavity is completely filled.

25. Production pattern equipment comprising cooperating drag and cope patterns having a plurality of spaced sections of different vertical height on the cope pattern, vent forming runners contacting the top of each of said sections of different vertical height and extending along the parting line between the drag and cope patterns.

30. Production pattern equipment comprising cooperating drag and cope patterns wherein the cope pattern has a plurality of spaced sections of different vertical height, the drag and cope patterns being contoured to extend the parting line vertically to points adjacent the top of each of said sections of different vertical height, and vent forming runners contacting each of said sections of different vertical height adjacent its uppermost portion and extending along the parting line of the drag and cope patterns.

35. A cope production pattern comprising a plate, a pattern impression projecting above the plate, a tapered section extending from the top of the pattern impression to the plate, and a vent forming runner contacting the top of the pattern impression and extending down the tapered section and along the surface of the plate to the marginal edge of the plate.

40. A production pattern comprising a base, a pattern impression projecting above the base, a vent forming runner contacting the top of the pattern impression and extending adjacent the pattern impression to the base and thence along the base.

45. A mold forming flask comprising a bottom plate, a frame surrounding the bottom plate,

a plurality of pattern carrying blocks detachably secured to the bottom plate, said pattern carrying blocks having a substantially flat base and a pattern projecting above the base to form a casting cavity in the mold, the blocks being contoured adjacent the patterns to extend the parting line of the mold to a point adjacent the top of each pattern, and a vent forming runner contacting the top of each pattern and extending along the contoured portion of the block and along the substantially flat base to the edge of each pattern carrying block.

12. The method of making production pattern equipment comprising mounting a master pattern having portions of different vertical height on a substantially flat surface, applying parting material adjacent the portions of different vertical height to provide tapered sections extending from the top of said pattern portions to the substantially flat surface, applying a vent forming strip to contact the portions of the pattern of different vertical height and extend down said tapered sections and along the substantially flat surface, applying a mold forming substance to form an impression of the pattern and parting material and vent forming strip, and casting production pattern equipment in said impression.

13. The method of making cooperating cope and drag production pattern equipment comprising applying parting material to a unitary pattern to eliminate back draft and establish a parting line between cope and drag molds, applying parting material to the pattern to extend the parting line between the cope and drag molds to points adjacent the top of the pattern, applying vent forming strips to contact the top of the pattern and extend along the parting material, applying mold forming substance to form an impression of the desired cope pattern and parting material and vent forming strip, forming cope production pattern equipment in said impression by a casting operation, forming another impression of the pattern and parting material, removing the parting material, applying mold forming substance to form an impression of the desired drag portion of the pattern formerly covered by the parting material, removing the pattern, and forming drag production pattern equip-

ment in said impression of the drag pattern and parting material.

14. The method of making from a master model production pattern equipment for forming vented molds comprising applying parting material to the master model to extend the parting to the top of the pattern, applying a vent-forming strip to the parting material, forming a cope impression of the model and parting material with the vent-forming strip in place, removing the vent-forming strip from the parting material, forming another impression of the pattern and parting material, removing the parting material, forming a drag impression of the model in said another impression with the parting material removed, and forming cope and drag patterns from the cope and drag impressions.

15. A mold comprising cope and drag sections having a generally horizontally disposed parting 20 when assembled in the casting position and cooperating to form a casting cavity extending into the cope section, the parting between the cope and drag sections being contoured adjacent the casting cavity extending into the cope section 25 to extend to a point adjacent the top of the casting cavity, and a vent passage communicating with the top of the casting cavity and extending along the parting line between the cope and drag sections to permit the escape of air from the casting 30 cavity.

16. The method of making cooperating cope and drag production pattern equipment having vent-forming strips from cooperating cope and drag patterns without vent-forming strips comprising applying parting material to the cope pattern to extend the parting to the top of the cope pattern impression, applying a vent-forming strip to the parting material, forming a cope impression of the cope pattern and parting material with the vent-forming strip in place, contouring the drag pattern in conformity with the parting material applied to the cope pattern with the vent-forming strip removed, forming a drag impression of the contoured drag pattern, and forming cope and drag production patterns from the cope and drag impressions.

RAYMOND J. MILLER.
